Patented Aug. 10, 1926.

UNITED STATES PATENT OFFICE.

JONATHAN C. MELOON, OF PROVIDENCE, RHODE ISLAND, ASSIGNOR, BY MESNE ASSIGNMENTS, TO GENERAL FIRE EXTINGUISHER COMPANY, OF PROVIDENCE, RHODE ISLAND, A CORPORATION OF DELAWARE.

FIRE-EXTINGUISHING SYSTEM.

Application filed April 3, 1922. Serial No. 549,007.

This invention relates to improvements in fire extinguishing systems. More particularly it relates to arrangements for supplying water to a sprinkler system in which two tanks are provided, one an open tank raised above the building in order to supply water by gravity, and the other a tank in which the water is under air pressure. Ordinarily both tanks are on the roof of the building, and they discharge into a common pipe which leads downward to the basement whence a riser, equipped if desired, with a dry pipe valve, goes up through the various floors to the top and connects with distributing pipes at each floor. In such a system it is customary to provide a check valve in the connection from the gravity tank to the down discharge pipe so that air and water can be maintained at a high pressure in the air pressure tank. This latter tank is normally open to the said down pipe but can be cut off therefrom by a second check valve provided in the connection between the two, which serves to prevent flow of water from the gravity tank into the pressure tank when the former is discharging into the system. Upon the opening of a sprinkler in the distribution system the air pressure diminishes with the flow of water from the air tank, but it has been found in some cases that when the water has been entirely exhausted therefrom the air following it remains of sufficient pressure to keep the check valve closed in the discharge connection from the gravity tank. There is especial danger of this occurring when the sprinkler which opens is on the top floor of the building so that the head of the gravity tank above the sprinkler is relatively low. In such cases the expected supply of water to the sprinkler system from the gravity tank fails. It is an object of the invention to provide for the prevention of the occurrence of such an air trap by automatically releasing the air from the air pressure tank when the pressure therein has fallen to a predetermined minimum which can be figured according to the initial pressure and the known volume of water to be evacuated thereby. The danger of failures described above has been so great that whereas a pressure of 80 or 90 lbs. to the square inch was standard practice for air tanks, and is desirable, insurance companies

now are accustomed to prohibit pressure above 60 lbs., which involves a definite lowering of standards of efficiency. By the present invention the normal pressure may be maintained at the former standard, or as much higher as may be desired, without failure of the supplementary supply from the gravity tank in case the water becomes exhausted from the air pressure tank.

This improvement is accomplished by providing an air escape valve and by associating it with a diaphragm, open to pressure of the air in the tank, that normally holds the said escape valve closed. The diaphragm is opposed by the pressure of the tank air upon the relatively small area of the escape valve, as it tries to escape therethrough, plus the pressure of a spring. When the air pressure is high, the greater area of the diaphragm causes the seating pressure to overcome the opening pressure on the valve. As the air pressure diminishes, the ratio between the valve closing pressure acting through the diaphragm and the valve opening pressure of air acting on the escape valve remains unchanged, but in magnitude the difference between these pressures gradually diminishes until there comes a time when it is less than the pressure by which the said spring supplements the opening pressure of air on the valve; whereupon the escape valve opens and air flows from the tank and thus reduces the pressure therein, and in the system, to such a low amount that it is less than the head of water in the gravity tank above the check valve in its discharge pipe, whereupon this check can no longer bar discharge from the gravity tank. Upon the opening of this valve the check valve in the connection to the air pressure tank closes, so that the supply from the gravity tank is thereafter wholly discharged into the sprinkler system.

In the accompanying drawings Figure 1 is an elevation partly in section of a building equipped with a sprinkler system embodying the invention;

Figure 2 is an enlarged view partly in section, showing the pressure release valve of the system.

Figure 3 is a section on line 3-3 of Figure 2.

Referring to the drawings a building,

with floors 10 shown in cross section, is protected by a sprinkler system whose water supply is maintained on the roof 12 in two tanks, one a gravity feed tank 14 mounted upon a tower 16, and the other an air pressure tank 18 in a housing 20. The separate discharge pipes 22 and 24 from these tanks connect with a downward extending pipe 26 leading to the basement, from which a riser 30 extends upward, through the building, to distributing pipes 32 underneath each ceiling, leading to the individual sprinklers 34. In the discharge pipe 22 from the gravity feed tank, above its connection with the pipe 26, there is a check valve 36 adapted to prevent water from rising into the tank when the pressure on the lower side of this check valve is greater than that above it. This is the normal condition of the system. when it is charged and awaiting the release of a sprinkler head, and is produced by pumping water into the two tanks, and allowing the system to fill up to a level indicated by the dotted line 38, whereupon the supply of water to the pressure tank is cut off. The gravity tank is, however, completely filled, its water being prevented from flowing into the air pressure tank, by a check valve 28, located in the connection from the latter tank to the down discharge pipe 26, and closing when the pressure on the lower side is greater than that above it, as when the gravity tank is being filled. While this is taking place air may be pumped into the pressure tank above the level of the water therein, as through pipe 37, until the predetermined pressure is reached, it being evident that as the air pressure builds up and exceeds that of the leg of water on the tower tank side the valve 28 will be opened and the valve 36 be closed. This normal static condition continues until the system begins to operate, that is upon the opening of one or more sprinkler heads.

The first discharge of water is to be from the pressure tank 18, and the check valve 36 is to be maintained closed until nearly all of this air tank water is exhausted, at which time the pressure in the air tank must have been reduced so that the check valve 36 is opened by the head and supply in the lower tank, to add its quota. It has been found in practice, however, that the check valve does not always open. This is due primarily to the head of the gravity tank above the open sprinkler being insufficient to overcome the pressure remaining in the tank 18 after its water has been discharged. To obviate this undesirable and dangerous situation, the present invention provides an automatic release valve for the air pressure tank which will open automatically when the pressure has been reduced to a certain point, sure to be reached before the water in that tank is fully exhausted, or at any rate before the

outflow of air will have been stopped by the balancing water column, assuming the highest sprinkler, to be the one opened. Such a valve indicated in Figure 1 by numeral 40, has two separate connections 42 and 44 70 with the top of the air tank above the water line 38, and a vent 46 opening to the atmosphere. The details of construction of one form of this valve are illustrated in Figure 2. 75

The valve comprises a two part casing 48 and 50 having annular flanges 48' and 50', adapted to register together and to secure between them a diaphragm 52, which constitutes a flexible partition dividing the interior of the casing into separate chambers, 54 and 56. The lower chamber 54 is directly connected to the tank 18 through the nipple 42 thereby exposing one side of the diaphragm to tank pressure. The upper chamber 56 is part of an escape passage from the tank to the atmosphere, being connected to the tank by pipe 44 and to the atmosphere by pipe 46. The flow of air through this passage is controlled by a valve 58 interposed in the upper chamber 56 and adapted to maintain the passage closed when a relatively high pressure exists in the tank 18, and to maintain the passage open, when this pressure is reduced to a predetermined point. This valve 58 seats upon a hollow plug 60 supported crosswise the chamber, through the hollow of which, a portion 62 of the valve stem projects upward from the valve to be engaged by a spring 64 which in turn extends further upward to seat against an adjustment plug 66 in the upper end of the casing 50. The portion 68 of the valve stem which projects downward from the valve, is connected by suitable means with the diaphragm 52. The sides of the upper portion 62 of the stem, where it passes through the opening in the plug seat 60 are flattened to provide passages by it, so that it is only necessary to move the valve from its seat a relatively small amount, as illustrated in Figure 2, to open the escape passage and thus vent the tank 18, for it is obvious that when the valve is opened, the pressure in the tank 18 can escape therefrom through the pipe connection 44, valve chamber 56 and pipe 46. When the tank is being charged with air this escape can be entirely cut off by merely closing the gate valve 70 in the pipe 44, 115 thereby saving all pressure in the tank from the movement it starts to build up. When the total pressure on the under side of the diaphragm exceeds that on its upper side including the force of the coiled spring the 120 diaphragm will flex to close the release valve 58. The force of the spring can be regulated by movement of the screw plug 66, which can be turned in or out upon removal of the closure cap 72, and loosening of the 125 binding nut 74. The adjustment of this 130

spring is made when the gate valve 70 is opened so that the pressure in the tank 18 is acting upon both sides of the valve 58 that is, upon the under side of the dia-
 5 phragm 52 and upon the upper end of the valve stem portion 62. The effect of the tank pressure alone would always keep the valve 58 closed, since the area of the dia-
 10 phragm is so much greater than the area of the valve, that the total pressure on the lat-
 15 ter, even though aided by the atmospheric pressure on the upper side of diaphragm and the weight of the moving parts is al-
 20 ways less than the pressure on the dia-
 25 phragm from below. Accordingly the pressure is adjusted to augment the air pressure on the valve stem so that as the latter is reduced in the tank 18 the pressure, being constant, will finally over-
 balance the diminishing difference of the air pressures and will cause the valve 58 to open. This immediately vents the pressure tank to the atmosphere, and allows what-
 ever excess pressure then exists in the tank to escape as heretofore described.

The creation of an air trap, due to the complete withdrawal of the water from the pressure tank before the check valve 36 opens, is prevented by the release valve 40, which can be set to operate at any predetermined degree of pressure sure to be reached in the pressure tank before its water is entirely gone. Upon the opening of this valve, and the consequent reduction of the pressure in the tank to that of atmosphere, the head of water in the gravity tank will force the check valve 36 open and close the check valve 28, thus allowing the gravity tank to discharge. This condition will continue until the head on the tower tank side of the check valve is equal to whatever head of water remained in the pressure tank upon the closing of the valve 28, whereupon this valve will open again, and thereafter both check valves will remain open until the total supply of water is discharged from both tanks.

I claim as my invention:

1. The combination with a sprinkler system having a gravity supply tank and a pressure supply tank arranged to discharge into the system upon the opening of a sprinkler head, of means adapted to withhold discharge from the gravity supply tank until the pressure in the other tank has been reduced to a predetermined degree, and means associated with said pressure tank, operative upon the lowering of its pressure to a degree higher than said predetermined degree, for automatically reducing the remaining pressure in said tank to the predetermined degree.

2. The combination with a sprinkler system having a gravity feed tank and an air pressure feed tank arranged to discharge

into a common feed pipe, of a check valve in the connection from the gravity tank adapted to hold back its water while the pressure of discharge from the pressure tank is greater than the pressure of the supply in the gravity tank; and an escape valve associated with the pressure tank and operative to release the air upon the reduction of the pressure therein to a predetermined degree, whereby the pressure of the discharge from the pressure tank becomes less than the pressure of the supply in the gravity tank.

3. A device adapted to be connected with the air space of a pressure tank of a sprinkler system, comprising a venting valve, means whereby it is maintained closed by relatively high pressure in said tank, and means whereby it is adapted to open upon the reduction of said high pressure to a predetermined degree, thereby venting said tank.

4. A releasing device for an air pressure supply tank, comprising a valve casing having a chamber connected continuously with the said tank, and having another chamber provided with a continuously open vent to the atmosphere and with a connection to said tank; a valve subjected to tank pressure in the first mentioned chamber and to opposite pressure of smaller total value in the other chamber whereby the valve tends to remain closed when the air pressure in the tank is above a predetermined degree; and a spring adapted to supplement said smaller pressure and to open said valve when the air pressure in the tank falls below said predetermined degree, thereby venting said pressure tank to the atmosphere.

5. A releasing device for an air pressure supply tank, comprising a valve casing having a chamber connected continuously with the said tank, and having another chamber provided with a continuously open vent to the atmosphere and with a connection to said tank; a valve subjected to tank pressure in the first mentioned chamber and to opposite pressure of smaller total value in the other chamber whereby the valve tends to remain closed when the air pressure in the tank is above a predetermined degree; and a spring adapted to supplement said smaller pressure and to open said valve when the air pressure in the tank falls below said predetermined degree, thereby venting said pressure tank to the atmosphere; there being means for varying said spring pressure thereby to operate the valve at different predetermined degrees.

6. A releasing device for an air pressure supply tank, comprising a valve casing having two chambers with separate connections with the tank, and one of them having a vent to the atmosphere; a diaphragm constituting a partition between the chambers,

exposed on one side to the tank pressure and on the other to the vent; a valve in the connection from the tank to the vented chamber with its operating stem secured to the 5 diaphragm, and means, associated with said stem, opposing the tank pressure on the diaphragm, and adapted to open the valve when the said pressure on the diaphragm is reduced, thereby venting the tank to the atmosphere.

7. A releasing device for an air pressure supply tank, comprising a valve chamber having a flexible wall exposed to tank pressure, and having a connection to the tank 15 and a vent to the atmosphere; a valve in said chamber between said connection and said vent, adapted to be closed by tank pressure on said flexible wall; and spring means operative upon said valve in opposition to 20 said tank pressure to open said valve when the tank pressure falls below a predetermined degree, thereby venting the tank to the atmosphere.

8. A releasing device for an air pressure supply tank comprising a valve chamber having a connection with said tank and a vent to the atmosphere; a valve in said chamber between said connection and said vent, having a valve stem projecting from 25 its opposite sides one end of which has an area exposed to the tank pressure, which area is greater than the area which on the other side of the valve is exposed to the tank pressure through said connection, whereby the

resultant pressure tends to maintain the 25 valve closed; and spring means arranged to act on the valve in conjunction with the air pressure on the lesser area, whereby upon the tank pressure being so reduced that the resultant air pressure on the valve stem is 40 less than the spring pressure, the said valve will open and vent the tank to the atmosphere.

9. An escape valve for a container whose contents are under pressure comprising a 45 valve adapted to vent said container and arranged to be held closed normally by pressure of contents therein when such pressure exceeds a predetermined limit; combined with means arranged constantly tending to open 50 the valve and adapted to do so when the pressure within the container falls below said predetermined limit.

10. In a fire extinguisher, the combination 55 with a supply main, a tank for containing water and air under pressure, and a gravity supply tank, both connected with the supply main, of check valves for preventing backward flow towards the tanks, the pressure tank having a vent, a valve for closing said 60 vent, and means to open said valve to vent the pressure tank upon the attainment of a predetermined condition in the pressure tank.

Signed at Providence, Rhode Island, this 65 thirtieth day of March, 1922.

JONATHAN C. MELOON.
